(57) **CLAIM**

The ornamental design for splash shield, as shown and described.

DESCRIPTION

FIG. 1 is a front, top, right perspective view of a splash shield according to a first preferred embodiment of my new design;

FIG. 2 is a top plan view of the splash shield of FIG. 1; FIG. 3 is a front elevational view of the splash shield of FIG. 1;

FIG. 4 is a bottom plan view of the splash shield of FIG. 1; FIG. 5 is a rear elevational view of the splash shield of FIG. 1;

FIG. 6 is a left side elevational view of the splash shield of FIG. 1;

FIG. 7 is a right side elevational view of the splash shield of FIG. 1;

FIG. 8 is a front, top, left perspective view of the splash shield of FIG. 1;

FIG. 9 is a front, top, right perspective view of a splash shield according to a second preferred embodiment of my new design;

FIG. 10 is a top plan view of the splash shield of FIG. 9; FIG. 11 is a front elevational view of the splash shield of FIG. 9;

FIG. 12 is a bottom plan view of the splash shield of FIG. 9;

FIG. 13 is a rear elevational view of the splash shield of FIG. 9;

FIG. 14 is a left side elevational view of the splash shield of FIG. 9;

FIG. 15 is a right side elevational view of the splash shield of FIG. 9; and,

FIG. 16 is a front, top, left perspective view of the splash shield of FIG. 9.

The dashed lines in FIGS. 1-16 are shown as environment only and represent manufacturing stitching and do not form part of the claimed design. The appearance of any portion of the article between the broken away symbols forms FIGS. 9-16 no part of the claimed design.
